[57] ABSTRACT

A generally elbow-shaped bushing muff or cover is utilized to provide an insulating cover for an angular connection between one or more conductors and a bushing terminal of a transformer. The muff is formed of a flexible insulating body consisting of a pair of generally U-shaped arm portions extending from a corner. One of the U-shaped arm portions has a bight portion readily mountable over the bushing terminal and has leg portions wrappable about each other and the terminal. The other of the U-shaped arm portions has a bight portion mountable over the conductor or conductors and has leg portions wrappable about each other and the conductor or conductors.

BUSHING COVER

This invention relates to a bushing muff, and more particularly, to a new and improved flexible bushing muff adjustably mountable about angular connections between at least one conductor and a bushing terminal of a transformer.

Distribution transformers normally have a bushing terminal projecting from a wall of the transformer so that one or several secondary leads or conductors can be coupled to the transformer. In most instances, the connection between the secondary leads and the bushing terminal is not only angular in configuration but also is exposed, causing a shock hazard both to humans and animals. In order to prevent or eliminate this shock hazard, the exposed connection must be covered with insulating material.

One type of commercially available insulating cover or protector includes a solid tubular elbow device which for installation requires the disconnection of the leads from the bushing terminal, the guiding or forcing of the leads through the device for reconnection of the leads, and the movement of the device over the bushing terminal. The required disconnection of the leads from the bushing terminal for installation makes this type of device unsatisfactory when additional leads are to be coupled to the terminal. Moreover, this type of device is normally so inflexible that virtually every installation requires a different size or shaped cover and is not readily usable when a plurality of leads are connected to a single terminal.

Another type of available protective cover is installable with the secondary leads connected to the bushing terminal. However, this type of protective cover normally can only accommodate a limited number of sized leads and bushings, and does not completely enclose the connection between the leads and the bushing terminal so that extensive taping must be done for the completion of the protection.

Still other covering devices have also been found unsatisfactory because they are not usable when a plurality of leads are connected to the terminal, are only usable with specific sized leads and/or bushings, or are not usable to cover angular connections.

Accordingly, objects of the present invention are to provide a new and improved bushing muff that covers and insulates angular connections between secondary leads and bushing terminals on a transformer; is usable with various sized leads and bushings; is installable without the disconnection of the secondary leads from the bushing terminal; substantially encloses the connection between the leads and the terminal without extensive supplemental taping; and is usable even though a multiplicity of secondary leads are coupled to the bushing terminal.

In accordance with these and many other objects, one embodiment of the present invention comprises a flexible insulating body forming a generally elbow-shaped bushing muff for use in covering an angular connection between at least one conductor and a bushing terminal of a transformer. The body of the bushing muff includes first and second generally U-shaped arm portions that are joined together at a corner. The first U-shaped arm portion has a bight portion readily mountable over the bushing terminal of the transformer and is severable along specified cut lines so as to fit over various sized bushing terminals. The second U-shaped arm portion also has a bight portion that is

mountable over the conductor coupled to the bushing terminal. Each of the U-shaped arm portions has a pair of legs extending from the bight portions which legs are wrappable and maintained about the terminal and conductor, respectively, so as to complete the insulation of the angular connection.

Many other objects and advantages of the present invention will become apparent from considering the following detailed description in conjunction with the drawings in which:

FIG. 1 is a perspective view of a bushing muff embodying the present invention;

FIG. 2 is a perspective view of the bushing muff of FIG. 1 partially installed about a transformer bushing terminal connection;

FIG. 3 is a perspective view of the bushing muff of FIG. 1 after being completely installed about the transformer bushing connection;

FIG. 4 is a cross-sectional view taken along line 4-4 of FIG. 3;

FIG. 5 is a cross-sectional view taken along line 5-5 of FIG. 3;

FIG. 6 is a side elevational view of the bushing muff of FIG. 1;

FIG. 7 is an end view of the bushing muff of FIG. 6;

FIG. 8 is another side elevational view of the bushing muff of FIG. 1; and

FIG. 9 is a bottom view of the bushing muff of FIG. 6.

Referring now to FIG. 1, there is shown a bushing muff or cover generally indicated as 20 embodying the present invention. The bushing muff 20 includes a generally U-shaped arm portion 22 having a bight portion 24 and a pair of legs or flaps 26 and 28 and a generally U-shaped arm portion 30 having a bight portion 32 and a pair of legs or flaps 34 and 36. The arm portions 22 and 30 extend from or join together at a corner 38 so as to form a substantially elbow-shaped body 40.

As indicated by an arrow 42, the muff 20, and more particularly, the bight portion 24, is mountable or placeable over a bushing terminal 44 projecting or extending from a wall 46 of a transformer or the like. When the bight portion 24 is positioned about the bushing terminal 44 so that the bushing terminal 44 extends into the corner 38 of the bushing muff 20, the bight portion 32 is positioned or mounted over or about a pair of secondary leads or conductors 48 and 50 angularly coupled to the bushing terminal 44. In order for the bushing muff 20 to insulate the angular connection between the bushing terminal 44 and the conductors 48 and 50, the leg 26 is folded or wrapped about the bushing terminal 44 and the leg 28 is then folded or wrapped about the leg 26 and the bushing terminal 44. Likewise, the leg 34 extending from the bight portion 32 is bent around or wrapped about the conductors 48 and 50 and then the leg 36 is wrapped about the leg 34 and the conductors 48 and 50.

More specifically and with reference to FIGS. 1 through 5, once the bushing muff 20 has been positioned over the bushing terminal 44, the leg 26 extending from one side of the bight portion 24 is wrapped about the bushing terminal 44 in the direction indicated by an arrow 52. While the leg 26 is held or maintained in its wrapped position about the bushing terminal 44, the leg 28 extending from the other side of the bight portion 24 is folded or wrapped about the leg 26 and the bushing terminal 44 as indicated by an arrow

54 in FIG. 1. Similarly, the leg 34 extending from one side of the bight portion 32 is bent around or wrapped about the conductors 48 and 50 in the general direction indicated by an arrow 56 in FIG. 1. While the leg 34 is held in place about the conductors 48 and 50, the leg 36 extending from the other side of the bight portion 32 is wrapped about the leg 34 and the conductors 48 and 50 as indicated by an arrow 58.

After the legs 26 and 28 have been wrapped about each other and the bushing terminal 44, a cable strap 60 or other securing device, such as a piece of tape or the like, is placed about the bight portion 24 and the folded legs 26 and 28. In this manner and as best seen in FIGS. 2 and 4, a generally tubular pocket or truncated substantially conical envelope 62 is formed about and insulates a substantial portion of the bushing terminal 44. Although the illustrated bushing terminal 44 is a spade-type bushing terminal having a bushing portion 64 and a terminal connector or spade 66 to which is coupled the pair of conductors 48 and 50 by appropriate fastening devices 68 and 70, respectively, the bushing muff 20 can be utilized with various other types of bushing terminals, such as a lug or regular type of bushing terminal, and with various numbers of conductors connected thereto. Moreover, since the bushing muff 20 is a flexible structure, the legs 26 and 28 can be wrapped tightly or loosely so that the end portion of the tubular pocket or envelope 62 fits snugly about the bushing 64 even though the bushing 64 may vary in size or diameter.

Once the arm portion 22 is secured about the bushing terminal 44, as described above and shown in FIG. 2, and the legs 34 and 36 have been wrapped about each other and the conductors 48 and 50, a cable strap 72 or the like is placed about the wrapped legs 34 and 36 and the bight portion 32 to secure the legs 34 and 36 in the wrapped position. As best seen in FIGS. 3 and 5, the wrapped legs 34 and 36 and the bight portion 32 of the arm 30 form a generally tubular pocket or truncated substantially conical envelope 74 which fits snugly about the conductors 48 and 50. The securing of the legs 34 and 36 about the conductors 48 and 50 completes the insulation of the bushing muff 20 about the angular connection between the bushing terminal 44 and the conductors 48 and 50 so that a generally tubular insulated elbow-shaped covering or body 75 is formed about the connection.

Of course, the number or sizes of the conductors 48 or 50 coupled to the bushing terminal 44 can vary depending on the individual transformer installation and/or requirements. Advantageously, notwithstanding the number or size of the conductors 48 and 50, the same bushing muff 20 can be utilized as a protective covering for the connection. If a lesser number of or smaller conductors are coupled to the bushing terminal 44, the legs 34 and 36 would only have to be wrapped more tightly about each other to provide the appropriate installation. On the other hand, if larger or more conductors were utilized, the legs 34 and 36 would merely be wrapped loosely so as to provide an appropriate fit about the conductors connected to the bushing terminal 44.

Moreover, as is readily apparent from FIGS. 1 through 5, by simply removing the straps 60 and 72 from the arm portions 22 and 30, respectively, the bushing muff 20 is readily removable from about the connection between the conductors 48 and 50 and the

bushing terminal 44 and either of the conductors 48 or 50 can be disconnected from the terminal connector 66 without disconnecting or disturbing the other conductor. In addition, more leads can be coupled to the terminal connector 66 without the disconnection of either of the conductors 48 and 50. Thereafter, the same bushing muff 20 can be replaced about the new connection in the same manner as described above.

The actual construction of the bushing muff 20 is best seen by referring to FIGS. 6 through 9. The body 40 of the bushing muff 20 is substantially formed of a flexible molded rubber, and each of the arm portions 22 and 30 are generally U-shaped and have arcuate end surfaces 76 and 78, respectively. The bight portion 24 of the arm 22 has a number of ridges 80, 82 and 84 and the bight portion 32 of the arm 30 has a pair of ridges 86 and 88 which lend strength to the arm portions 22 and 30 and aid in the proper wrapping and securing of the legs 26, 28, 34 and 36. The arm portions 22 and 30 join together at the corner 38 to form a pocket or cavity 89 into which the terminal connector 66 is fittable.

The leg 26 extending from the bight portion 24 has a generally curvilinear edge portion 90 that extends generally away from the corner 38 and towards the arcuate surface 76 of the arm 22 to form a rounded tip 92 for the end of the leg 26. The leg or flap 28 extending from the other side of the bight portion 24 is somewhat longer than the leg 26 and has generally straight edges 94 and 96. Since the leg 26 is shorter than the leg 28 and is rather pointed at its end 92, the leg 26 is easily wrappable about the bushing terminal 44 and under the leg 28.

The leg 34 extending from one side of the bight portion 32 is relatively short in length and has edge portions 98 and 100. The edge surface 98 extends generally parallel and relatively close to the edge surface 94 of the flap 28 so as to form or define a rather small or narrow slit or open area 102. The leg 36 extending from the other side of the bight portion 32 is generally longer than the leg 34 and has a rather straight edge 104. Since the leg 34 is shorter than the leg 36, the leg 36 is easily wrappable about the conductors 48 and 50 and the wrapped leg 34.

A side edge 106 of the leg 36 is generally curvilinear and extends generally parallel and relatively close to the edge surface 90 of the leg 26 to form or define a rather small or narrow slit or open area 108. By having the slits or open areas 102 and 108 formed between the legs 28 and 34 and the legs 26 and 36, respectively, the various legs 26, 28, 34 and 36 are readily wrappable about the bushing terminal 44 and the conductors 48 and 50 so that the bushing muff 20 is easily installed about the angular connection between the bushing terminal 44 and the conductors 48 and 50. Moreover, the orientation of the relatively narrow slits 102 and 108 relative to each other assures that when the flap 28 is wrapped about the flap 34 and the flap 36 is wrapped about the flap 34 little or no apertures will remain through which access might be had to the exposed portions of the connection between the conductors 48 and 50 and the bushing terminal 44; thus eliminating any possible shock hazard.

In addition, the curvilinear or arcuate edges 78 and 106 of the flap 36 tend to form the base and top of the truncated substantially conical envelope 74 resulting from or formed by the wrapping of the flap 36 over the flap 34 and the conductors 48 and 50. This conical

form of the envelope 74 assures a snug fit over the conductors 48 and 50 even though the spade 66 and the connecting lug or fasteners 68 and 70 may be considerably bulkier than the conductors 48 and 50. Likewise, the curvilinear edge 76 of the flaps 26 and 28 provides the generally conical shape of the envelope 62 when the flap 28 is wrapped about the flap 26, the bushing 64 and the spade 66. This assures that the envelope 62 will snugly fit on the bushing 64 even if the connections between the bushing terminal 44 and the conductors 48 and 50 are somewhat bulky. 10

Extending about the arm portion 22 are a pair of indicating lines or cut lines 110 and 112. The indicating lines 110 and 112 indicate where the legs 26 and 28 and the bight portion 24 should be severed if various sized bushing terminals are being covered by the bushing muff 20. For example, if the bushing terminal utilized is not as long as the illustrated bushing terminal 44, the arm portion 22 can be severed along the indicating line 110 prior to the installation of the bushing muff 20 about the bushing terminal. Similarly, if the bushing terminal is substantially shorter than the illustrated bushing terminal 44, the arm portion 22 can be severed along the indicating line 112. In either case, the end of the bight portion 24 is still defined by the ridge 82 or the ridge 80. 15

While the present invention has been described in connection with the details of one illustrative embodiment thereof, it should be understood that these details are not intended to be limitative of the invention except insofar as set forth in the accompanying claims. 30

What is claimed and desired to be secured by Letters Patent of the U.S. is:

1. A flexible insulating body for forming a generally elbow-shaped muff over an angular connection between at least one conductor and a bushing terminal of a transformer, said body comprising first and second generally U-shaped arm portions extending from a corner, said first arm portion having a first bight portion mountable over said bushing terminal and having first and second generally flexible legs extending generally parallel to each other away from said first bight portion on opposite sides of said bushing terminal, said first leg being wrappable about said bushing terminal and said second leg being wrappable about said first leg and said bushing terminal, and said second arm portion having a second bight portion mountable over said conductor and having generally flexible third and fourth legs extending generally parallel to each other away from said second bight portion on opposite sides of said conductor, said third leg being wrappable about said conductor and said fourth leg being wrappable about said third leg and said conductor. 35

2. The muff as set forth in claim 1 wherein said third leg is shorter than said fourth leg. 55

3. The muff as set forth in claim 1 wherein said first leg is shorter than said second leg.

4. The muff as set forth in claim 1 wherein said first bight portion and said first and second legs have indicating means along which said first arm portion is severable in order to properly fit about said bushing terminal. 60

5. The muff as set forth in claim 1 wherein said body is formed of flexible molded rubber. 65

6. A flexible protective cover for encompassing an angular connection between at least one conductor and

a bushing terminal of transformer, said cover comprising:

a generally elbow-shaped body portion having first and second substantially U-shaped arms extending from a corner, said first arm having a first bight portion mountable over said bushing terminal and first and second generally flexible flap means extending from the first bight portion generally parallel to each other, said first flap means being wrappable about said bushing terminal and said second flap means being wrappable about said first flap means and said bushing terminal, said second arm having a second bight portion mountable over said conductor and third and fourth generally flexible flap means extending from the second bight portion generally parallel to each other, said third flap means being wrappable about said conductor and said fourth flap means being wrappable about said third flap means and said conductor, and securing means securing said second flap means about said first flap means and securing said fourth flap means about said third flap means. 20

7. The cover as set forth in claim 6 including a plurality of ridges on said first and second bight portions. 25

8. The cover as set forth in claim 6 wherein said body portion is formed of a molded rubber. 30

9. The cover as set forth in claim 6 wherein said first and second arms and said corner form a pocket into which said connection is fittable. 35

10. A flexible insulating body for forming a generally elbow-shaped muff over an angular connection between at least one conductor and a bushing terminal of a transformer, said body comprising first and second generally U-shaped arm portions extending from a corner, said first arm portion having a first bight portion mountable over said bushing terminal and having first and second legs, said first leg being wrappable about said bushing terminal and said second leg being wrappable about said first leg and said bushing terminal, said second arm portion having a second bight portion mountable over said conductor and having third and fourth legs, said third leg being wrappable about said conductor and said fourth leg being wrappable about said third leg and said conductor, said wrapping of said second leg about said first leg and said fourth leg about said third leg is facilitated by a first slit formed between said first and fourth legs and a second slit formed between said second and third legs. 40

11. A flexible protective cover for encompassing an angular connection between at least one conductor and a bushing terminal of a transformer, said cover comprising:

a generally elbow-shaped body portion having first and second substantially U-shaped arms extending from a corner, said first arm having a first bight portion mountable over said bushing terminal and first and second flap means extending from the first bight portion, said first flap means being wrappable about said bushing terminal and said second flap means being wrappable about said first flap means and said bushing terminal, said second arm having a second bight portion mountable over said conductor and third and fourth flap means extending from the second bight portion, said third flap means being wrappable about said conductor and said fourth flap means being wrappable about said third flap means and said conductor, and each of

said first, second, third and fourth flap means having at least one curvilinear edge so that a first generally truncated substantially conical envelope is formed when said second flap means is wrapped about said first flap means and a second generally truncated substantially conical envelope is formed

when said fourth flap means is wrapped about said third flap means, and securing means securing said second flap means about said first flap means and securing said fourth flap means about said third flap means.
